E. G. PERKINS,
CASING CONSTRUCTION FOR RHEOSTATS.
APPLICATION FILED JAN. 6, 1922.

1,437,268.

Patented Nov. 28, 1922.

UNITED STATES PATENT OFFICE.

EARL G. PERKINS, OF YOUNGSTOWN, OHIO.

CASING CONSTRUCTION FOR RHEOSTATS.

Application filed January 6, 1922. Serial No. 527,499.

To all whom it may concern:

Be it known that I, EARL G. PERKINS, a citizen of the United States, residing at Youngstown, in the county of Mahoning 5 and State of Ohio, have invented certain new and useful Improvements in Casing Constructions for Rheostats, of which the following is a specification.

This invention relates to rheostats and the 10 like, and more particularly to a novel casing construction for supporting and housing the rheostat unit. However, while the drawings, specifications and certain claims are prepared with special reference to rheostats, 15 involving resistance coils, the invention will be equally useful and advantageous in connection with various translating devices, such for instance, as a heating unit involving reactance coils.

20 A primary object of the invention is to provide a construction that may be easily manufactured and quickly assembled, and which affords convenient access to the rheostat unit and the wiring connections between 25 the same and the controller device.

A further object is to provide a novel 30 rheostat unit adapted to carry the spools for the resistance wires. In that connection the invention provides a unit which greatly facilitates the assembly and attachment of 35 the connections between the resistance wires and the contacts of the switch-board as well as the terminal board.

With the above and other objects in view 40 which will more readily appear as the nature of the invention is better understood, the same consists in the novel construction, combination and arrangement of parts herein-after more fully described, illustrated and claimed.

A preferred and practical embodiment of the invention is shown in the accompanying drawings in which

Figure 1 is a side elevation, partly in section, of the improved casing construction.

Figure 2 is a vertical sectional view taken on the line 2—2 of Figure 1.

Figure 3 is a detail elevation of the resistance spool carrier.

Figure 4 is a detail elevation of one end of the casing.

Similar reference characters designate corresponding parts throughout the several figures of the drawings.

55 The casing or housing constituting the present invention preferably includes the

novel end frame members 1—1 which are of duplicate formation, thereby materially economizing in manufacture, as only one form or mold is necessary. Therefore, as 60 these members are of identical construction, the description of one will suffice for both.

As will be observed from Figures 1, 2 and 3, the said end frames are preferably of substantially rectangular formation, having at 65 their lower sides the feet 2 for supporting and attaching the casing in the desired location. The inner edge portion of said frame is formed with a rabbeted seat 3 for receiving either the insulating switch-board 4 or terminal board 4^a, and for the purpose of holding such member in the seat, the frame may be provided at the corners or other suitable locations with screw threaded 70 sockets for receiving the screws 5 or equivalent fastenings carrying the washers 6. This arrangement makes it possible to easily place and remove the insulating members or boards by simply inserting or removing the screws 5 from the sockets. Also the lower 75 member 7 of the frame constitutes a rest or shoulder for receiving an insulating platform 8 which may be secured to each end frame by screws 9 or the like. And, as shown in Figure 1, this platform serves to 80 unite and space the opposite end frames 1—1 in their assembled relation.

The outer edge of each frame is provided in its top and vertical sides with a rabbeted seat 10 for receiving a ventilating cover 11, 90 which may be of open or screen-like formation as indicated in Figure 1, and may be held to the end frames by suitable fasteners 12.

The rheostat unit or spool carrier C for 95 the resistance wires preferably consists of a pair of insulating wall members 13 and 14 adapted to receive the supporting rods or elongated bolts 15, the heads 15^a and nuts 15^b of which engage the outer faces of the 100 wall members thereby to clamp the ends of the insulators or spools 16 against the inner faces thereof as shown in Figure 3. When the wall members and spools are assembled by tightening the nuts 15^b on the supporting 105 rods, a rigid and conveniently removable carrier unit is provided. As shown in Figure 1 this carrier merely rests loosely upon the platform 8 in such manner that it may be readily removed and replaced when desired, while at the same time any individual spool may be dismounted from its position 110

and replaced without disturbing any of the other spools in the general assembly. In the assembled construction, the wire connections between the resistance coils and the contact terminals serve to hold the unit against longitudinal movement, while the cover 11 serves the same purpose as against vertical or lateral movement.

From the foregoing it will be apparent that the present construction provides a simple and practical casing construction which has many advantageous features. By reason of the structural features of the end frames, the insulating switch-board and terminal elements 4 and 4^a may be readily fitted with their contacts and terminals and thereafter conveniently assembled in the frame. Furthermore, the end frames may be readily connected by the insulating platform 8 and the cover 11 which interfit with the proper portions of the frame to make a neatly furnished as well as substantial construction.

Without further description it is thought that the features and advantages of the invention will be readily apparent, and it will be understood that changes in the form, proportion and minor details of construction may be resorted to without departing from the spirit of the invention or scope of the appended claims.

I claim:

1. A casing of the class described, including upright end frames having supporting feet, an insulating platform arranged between and connecting said end frames, and insulating terminal boards fitted in the open portions of said end frames.

2. A casing of the class described, including upright end frames, an insulating platform for connecting and spacing said end frames, insulating terminal or switch boards detachably fitted in said frames, and a cover detachably connected to said end frames.

3. A casing of the class described, including an upright end frame of substantially rectangular formation and provided with

supporting feet, said frame having a terminal or switch board receiving seat formed at its inner edge, and a cover receiving seat formed at its outer edge.

50

4. A casing of the class described, including upright end frames of duplicate construction, said frames being arranged reversely to each other and provided with terminal-board receiving seats and cover receiving seats, an insulating platform connecting the lower portions of said frames, a rheostat unit supported on said platform, a cover having its ends fitted in the cover receiving seats of the end frames, and means 60 for securing the cover to said frames.

55

5. A casing of the class described including upright end frames, an insulating platform arranged between and connecting said frames, terminal boards detachably fitted in said frames, a rheostat unit adapted to rest on said platform, and a cover fitted to said end frames for housing said rheostat unit.

65

6. A casing of the class described, including an insulating platform and a rheostat 70 unit adapted to be loosely supported by said platform and including opposite end walls of insulation, insulators for the resistance wires arranged between said walls, and clamping bolts for connecting the end walls 75 and clamping the insulators therebetween.

75

7. A casing of the class described, including end members, an insulating platform and a rheostat unit adapted to be loosely supported upon said platform and including 80 opposite end walls of insulation, insulators for the resistance wires arranged between said walls, and bolts for connecting the end walls and clamping the insulators therebetween.

85

In testimony whereof I hereunto affix my signature in the presence of two witnesses.

EARL G. PERKINS.
